United States Patent Office

Des. 184,896
Patented Apr. 14, 1959

184,896

REFRIGERATOR CABINET

Ray C. Sandin, Northbrook, Ill., assignor to General
Electric Company, a corporation of New York

Application July 29, 1957, Serial No. 47,130

Term of patent 7 years

(Cl. D67—3)

Fig. 3.

Fig. 5.

Fig. 4.

Fig. 1 is a front elevation of a refrigerator cabinet embodying my new design;

Fig. 2 is a right side elevational view thereof;

Fig. 3 is a fragmentary section of a corner of the door taken on line 3-3 of Figure 1;

Fig. 4 is a fragmentary vertical section looking in the direction of the arrows 4-4 of Fig. 1; and

Fig. 5 is a left side elevational view.

I claim:

The ornamental design for a refrigerator cabinet, substantially as shown.
